Filed Aug. 19, 1966, Ser. No. 3,538

Term of patent 14 years

(Cl. D52—6)

FIG. 2

FIG. 1

FIG. 3

FIG. 4

FIGURE 1 is a top plan view of a measuring tape and the like showing my new design;

FIGURE 2 is a side elevational view thereof;

FIGURE 3 is an end elevational view thereof; and

FIGURE 4 is a fragmentary plan view thereof to an enlarged scale.

The bottom of the measuring tape is plain in appearance.

The dominant feature of my design resides in the full line portions of the drawing.

I claim:

The ornamental design for a measuring tape and the like, as shown and described.
